TRACK CIRCUIT APPARATUS

Howard A. Thompson and George W. Baughman,
Edgewood, Pa., assignors to The Union Switch
& Signal Company, Swissvale, Pa., a corpora-
tion of Pennsylvania

Application September 27, 1939, Serial No. 296,830

4 Claims. (Cl. 246—34)

Our invention relates to track circuit apparatus and more specifically to apparatus of this character which provides protection against false energization of a track relay due to failure of the insulated rail joints which separate adjoining track circuits.

One object of our invention is to provide apparatus such that the failure of a rail joint will be detected by a release of the track relay for the associated section. Another object is to eliminate the necessity for using polarized or two-position track relays and staggering the polarity of adjoining track circuits to avoid false relay operation. A further object is to provide a path for the flow of propulsion current around the insulated rail joints without introducing any "dead" sections of track in which the presence of a car could not be detected. Other objects and advantages will become clear as the description progresses.

We shall describe one form of apparatus embodying our invention and shall then point out the novel features thereof in claims.

The accompanying drawing is a diagrammatic view showing one form of apparatus embodying our invention as applied to a propulsion railroad employing alternating current track circuits.

In railway signaling track circuits, provision must be made against false energization of the track relays due to leakage of current from adjoining track circuits over rail joints in which the insulation has been broken down. In general, this false energization can be prevented by using polarized or two-element track relays and staggering the polarity in adjoining track circuits so that the leakage current will cause a reversal or deenergization of the affected track relay. Where alternating current track circuits are employed, the use of two-element track relays presents a problem due to the fact that when the transmission line is sectionalized, one element of the track relay at the sectionalizing location may receive current from one source of supply while the other element receives its energy from a different source, thus rendering the relay inoperative. Accordingly, difficulties are encountered with two-element alternating current relays where sectionalizing must be employed.

The apparatus embodying our invention does not require a two-element track relay and provides broken-down insulated rail joint protection in any alternating current track circuit, whether on a steam road or in electric propulsion territory. The insulated rail joints which we employ may be of the usual type but these

are so arranged in conjunction with a relatively short insulated section of track and with certain inductances connected across the rails at the rail joint locations that in the event of breakdown of the insulation, the failure will be indicated by a release of the associated track relay.

The foregoing protection is obtained due to the fact that a failure of the insulation at the rail joint will short-circuit a portion of the inductance which is connected across the rails, thus partly short-circuiting the track circuit. Accordingly, our invention permits the use of single element track relays energized from an alternating current track circuit, and eliminates the transmission line sectionalizing problem without sacrificing broken-down rail joint protection.

Referring now to the drawing, the reference characters 1 and 1a designate the two rails of a stretch of track divided by the insulated rail joints 2a, 2b, 2c, and 2d to form two adjoining track circuit sections A—C and C—E. Each of these track sections is provided with an alternating current track relay TR connected across the rails at one end of the section and receiving energy from a track transformer T connected across the rails at the other end of the section through a suitable current limiting impedance X. Each track transformer is energized from a suitable source of alternating current (not shown) having the terminals BX—CX. The signal S at location C is controlled over the contacts 7—8 and 7—9 of the track relay TR1 at the same location, in the usual manner. The particular control circuits for this signal are well known and have not been shown in detail in order to simplify the disclosure.

It will be noted that we make use of two insulated sections of rail 10 and 11 at the location where the two track sections A—C and C—E adjoin for a purpose which will become clear as the description progresses. These rail sections may represent a standard rail length such, for example, as 32 feet and therefore do not ordinarily require any cutting of the rail. The impedance bonds 1B and 1B1 as well as the connectors 12, 14 and 15 are provided for the purpose of establishing a path for the flow of propulsion current around the various insulated rail joints. For example, propulsion current flowing in the upper rail 1 may take a path through wire 13, upper half 3 of the impedance bond 1B, wire 14, rail section 10, wire 12, rail section 11, wire 15, and upper half 5 of the impedance bond 1B1, to the upper rail 1. Similarly, propulsion current flowing in the lower rail 1a may take a path through

the lower portion 4 of impedance bond IB, wire 14, rail section 10, wire 12, rail section 11, wire 15, and lower half 6 of the impedance bond IB!, to the lower rail 1a. Since the propulsion current flows in opposite directions in the two halves of each impedance bond, the induction effects due to the propulsion current are substantially neutralized so that no appreciable propulsion potential is impressed across the two rails of the track.

10 The track circuit current flows from the track transformer to the respective track relay in the usual manner, it being observed, however, that the rail sections 10 and 11 do not receive any track circuit current. Due to the arrangement of the 15 apparatus, the rail lengths 10 and 11 do not represent "dead" sections of track but, on the contrary, are responsive to the presence of a train or car either partly or wholly within the section B—D. The rail joints 2b and 2c may be located 20 approximately opposite one another whereas the joints 2a and 2d are preferably staggered, one to the left and the other to the right of the rail joints at the signal location.

With the foregoing arrangement, should a car 25 stand wholly between the rail joints 2a and 2b, for example, the car will obviously place a short-circuit upon the upper half 3 of the impedance bond IB, thus partly short-circuiting the track circuit so that relay TR will remain released. 30 Similarly, if the car is wholly between the rail joints 2c and 2d, it will short-circuit the lower half 6 of the impedance bond IB! so that relay TR! will release. The shunting sensitivity of a car within the sections B—C and C—D will not 35 be so high as that which is obtainable within the sections A—B and D—E for the reason that the inter-rail voltage in the former two sections is about one-half of that effective in the latter sections. This shunting sensitivity is, however, 40 adequate for satisfactory operation in practice.

A failure of either rail joint 2a or 2d will obviously short-circuit the respective winding 4 or 45 5 of the associated impedance bond IB or IB!, whereupon the track circuit voltage will be reduced to practically zero and the fault will accordingly be indicated by a release of the respective track relay even though the track is unoccupied at the time. Similarly, a failure of either rail joint 2b or 2c will place a short-circuit 50 on the respective winding 3 or 6 of the associated impedance bond, thereby also causing a release of the track relay for the associated section. On the other hand, a break in any of the connectors 14, 12, and 15 or in the rails 10 and 55 11 will be evidenced by a partial or total interruption of the propulsion current. From the foregoing, it will be apparent that we have provided track circuit apparatus which effectively eliminates the danger arising from a failure of the insulated rail joints in a simple and safe manner.

Although we have herein shown and described only one form of track circuit apparatus embodying our invention, it is understood that various 60 changes and modifications may be made therein within the scope of the appended claims without departing from the spirit and scope of our invention.

Having thus described our invention, what we 65 claim is:

1. In combination, a stretch of railway track divided into two track circuit sections by means

of an intermediate portion of track separated from both said sections by insulated rail joints, a source of alternating current connected across the rails of one said section, a track relay connected across the rails of the other said section, 5 an impedance bond for each of said sections connected across the rails of its respective section, a connection from the mid-point of one impedance bond to one rail of said intermediate track portion, a connection from the mid-point of the 10 other impedance bond to the other rail of said intermediate track portion, and a connection joining the two rails of said intermediate track portion.

2. In combination, a stretch of railway track, 15 a first insulated rail joint in one rail of said track, a second insulated rail joint in the other rail of said track approximately opposite said first insulated rail joint, a first insulated rail portion to the right of said first rail joint, a second insulated rail portion to the left of said second rail joint, a first track circuit to the left of said first insulated rail joint and terminated thereby, a second track circuit to the right of said second insulated rail joint and terminated thereby, a 25 source of alternating current for said first track circuit, a track relay for said second track circuit, a first and a second reactor connected respectively across the rails of said first and said second track circuit, a connection from the mid- 30 point of said first reactor to said second rail portion, a connection from the mid-point of said second reactor to said first rail portion, and a connection joining said first and said second rail portions. 35

3. In combination, a stretch of railway track divided into two track circuit sections by means of an intermediate portion of track separated from both said sections by insulated rail joints, the two rails of said intermediate track portion 40 being staggered with respect to each other, a source of alternating current for one of said sections, a track relay for the other of said sections, a reactor for each of said sections connected across the rails of its respective section, a connection from the mid-point of one reactor to one rail of said intermediate track portion, a connection from the mid-point of the other reactor to the other rail of said intermediate track portion, and a connection joining the two rails of 45 50 said intermediate track portion.

4. In combination, a stretch of railway track divided into two track circuit sections by means of an intermediate portion of track separated from both said sections by insulated rail joints, 55 the two rails of said intermediate track portion being staggered with respect to each other, a track transformer having its secondary winding connected across the rails of one of said sections, a current-limiting device included in the connection of said secondary winding, a track relay connected across the rails of the other of said sections, a reactor for each of said sections connected across the rails of its respective section, a connection from the mid-point of one reactor to one rail of said intermediate track portion, a connection from the mid-point of the other reactor to the other rail of said intermediate track portion, and a connection joining the two rails of 60 65 70 said intermediate track portion.

HOWARD A. THOMPSON.
